RENEWABLE FUSE PLUG

John W. Hooley, Larchmont, N. Y.

Application February 7, 1933. Serial No. 655,661

2 Claims. (Cl. 200—130)

This invention relates to devices for effecting quick re-connection of broken electrical circuits, and refers particularly to what are commonly known as fuse plugs.

5 Fuse plugs of the present common or well known type have soldered connections so that the device as a whole is practically sealed tight at the factory and can not be taken apart without entirely destroying its utility. Therefore, if the fuse member of such a plug blows out due to overload, short circuit, etc., the entire fuse plug must be thrown away. When this happens, if one has no new plug of the right kind conveniently at hand, he is liable to attempt to substitute for the blown 10 fuse something to serve as one, with the result that the circuit may be badly overloaded, or grounded, or short-circuited, and cause great damage, because, after all, the fuse is only a safety valve for the protection of the circuit. For such elaborate electrical devices as are now manufactured and used, such as electric irons, electric heaters, electrical instruments, lamps, fixtures, motors, etc., if the circuit is not properly limited 15 as to its current-carrying capacity and protected adequately by just the proper fuse therefor, the result is apt to be not only monetary loss due to damage to appliances connected to the circuit, but also a fire or personal injury. Therefore, a most vital necessity for protection to life and property 20 is in the proper and immediate operation of electric fuses or circuit-protective devices.

One of the objects of my invention is to provide fuse plugs with fuse members which are easily renewable without affecting the plug itself, so that 25 a single plug may be used repeatedly by simply substituting a new fuse member for a blown one, this only necessitating the having at hand a small compact plurality of duplicate members of the same kind as the one blown.

30 Another object is to effect economy in space and in the cost to users, by enabling a single plug and, for instance, a dozen extra fuse members, to ultimately serve the purpose of thirteen fuse plugs of the present type.

Another object is to provide renewable fuse plugs 35 which require no more space than any of the present well-known types, and which may be utilized in all cut-outs the same as previous types.

With said objects in view, and others herein- 40 after referred to, my invention consists in the construction and combination of parts substantially as hereinafter described and claimed.

Of the accompanying drawing:

Figure 1 represents, in vertical section, a preferred embodiment of my invention.

Figure 2 is a plan view of the same.

Figure 3 is a perspective view of one of the fuse members, enlarged.

Similar reference characters designate similar parts or features in all of the views.

So far as concerns the plug member, the body 12 of insulating material, and its conducting shell 13, shaped to provide an externally threaded portion to engage the usual threaded interior of a socket, is of the usual type.

A cover consisting of a transparent disk 14, of glass or mica, is secured to the top of the body by a screw ring 15, and at the bottom of said body is a screw 16 the outer end of which engages and secures the contact member 17. The screw also passes through a washer 18 bearing on the inner surface of the body 12 at its bottom.

Referring now to Figure 3 which illustrates a preferred form for the most important feature of my present invention, the fuse member 19 has slotted ends 20 one of which is adapted to be secured under the head of the screw 16 as illustrated in Figure 1, and the other slotted end is adapted to be secured under the head of an upper screw 21 which extends through the side wall of the body 12 and engages the conducting shell 13.

The fuse member is of such length that it can be bent to have an intermediate portion of its length offset laterally so as to extend somewhat vertically near the side of the body 12 that is opposite the location of the screw 21, for a purpose presently described. Said fuse member is preferably of the type illustrated and claimed in Re-issue Letters Patent No. 16,503, issued to me December 14, 1926, the said fuse member having openings therein in the form of characters determining and indicating the capacity of the fuse. Said patent may be referred to for a full explanation of the advantages of the fuse being made so as to indicate on its face its current capacity in clear and unmistakable terms.

Movably or removably mounted in the body 12 is a barrier or guard disk 22 having a marginal recess 23, preferably of such material as mica which is sufficiently transparent to permit visible inspection of the condition of that portion of the fuse member which is below it, and which is sufficiently reflective to aid the inspection of the condition of that portion of the fuse member which is above it, such inspection being permitted by the transparent disk 14. As illustrated in Figure 1, the interior of the body 12 is slightly tapered, and the barrier disk 22 is of such diametrical size as to be frictionally retained substantially in a mid-way position so that the portion

of the fuse member which extends along near one side of the chamber in the body 12 will be accommodated in the recess 22 of the barrier.

The washer or guard disk 22 serves to prevent any molten metal that exists after a blow-out of the fuse 19 from causing or permitting an arc between those portions of the fuse remaining adjacent to the screws. Such jumping of the current would be liable to cause such heat as to damage the cut-out block itself and other adjacent devices or structures.

The body 12 is provided with a downwardly and outwardly directed vent hole 24 to permit gases to escape when the fuse member blows.

15 The utility and advantages of the device will now be explained:

Assuming that a user purchases and has at hand one or more of the renewable fuse plugs, with a plurality, say six, of duplicate fuse strips of the 20 same kind as the one already in the plug member, then the space required, and the cost to him, will be far less than for seven ordinary fuse plugs.

Assuming that the fuse becomes blown in the device that is in use, it is apparent and visible 25 through the disk 14. When the device is unscrewed from its socket in the fuse block or cut-out, the ring 15 is unscrewed and the disk 14 removed. Then a screw-driver can be used to remove the screw 21, and the washer or barrier 30 22 is removed. If the latter is somewhat stuck, its removal from its frictionally held seat can be readily effected by inserting the point of the screw-driver in the recess 23 and loosening said barrier. After then loosening the screw 16, the 35 burnt-out fuse member is removed. A new fuse member 19 then has its lower end secured under the head of the screw 16, the barrier 22 returned to the position illustrated (the fuse member being inherently sufficiently flexible to permit this to be 40 done), the upper end of the fuse member then secured under the head of the screw 21, and the disk 14 and ring 15 returned to position. These operations can be effected in approximately 30 seconds, so that a new fuse quickly takes the place 45 of a blown one at a fraction of the cost of an entire new fuse plug of common type.

The vent 24 is directly over the recess 23 in the

margin of the guard disk 22, and said vent extends in a downwardly and outwardly leading direction. Therefore, if the fuse is burnt out any gases resulting therefrom will escape through the vent hole into the air surrounding the fuse plug so as to eliminate possibility of fire in the event that any flame is carried as a portion of the gas.

Another advantage is that building owners, engineers, or those in charge of building operations, can keep in stock a large supply of fuse members 19 at relatively low cost as compared with a stock of complete fuse plugs, and requiring but a small space for storage.

Another and important advantage is that correct re-conditioning of a blown-out device is ensured, because the two members consisting of the plug member and the fuse member are of such relative pre-designed shapes or proportions and have such co-acting connecting members as the screws 16, 21, and the slotted ends 20 of the fuse strips, that an improper fuse member could not be installed in the plug member.

Having now described my invention, I claim:

1. A renewable fuse plug consisting of a plug member having a tapering chamber, a flash guard disk frictionally engaging the wall of said tapering chamber at an intermediate point thereof, said guard disk having a marginal recess, and a fuse member the upper portion of which extends transversely across the chamber above said guard disk and an intermediate portion of which extends through the said marginal recess of the guard disk.

2. A renewable fuse plug consisting of a plug member having a tapering chamber, a flash guard disk frictionally engaging the wall of said tapering chamber at an intermediate point thereof, said guard disk having a marginal recess, and a fuse member the upper portion of which extends transversely across the chamber above said guard disk and an intermediate portion of which extends through the said marginal recess of the guard disk, the plug member having a downwardly and outwardly directed vent hole in the upper portion of its wall directly over the marginal recess in the guard disk.

JOHN W. HOOLEY.
